UNITED STATES PATENT OFFICE.

JAMES C. GARNER, OF HOUSTON, TEXAS, ASSIGNOR, BY MESNE ASSIGNMENTS, TO THE GARNER GIN COMPANY, INC., OF HOUSTON, TEXAS, A CORPORATION OF TEXAS.

COTTON SEPARATOR.

1,409,541.

Specification of Letters Patent. Patented Mar. 14, 1922.

Application filed March 17, 1919, Serial No. 283,201. Renewed July 6, 1921. Serial No. 482,872.

To all whom it may concern:

Be it known that JAMES C. GARNER, a citizen of the United States, residing at Houston, in the county of Harris and State 5 of Texas, has invented certain new and useful Improvements in a Cotton Separator, of which the following is a specification.

This invention relates to new and useful improvements in a cotton separator.

10. The object of the invention is to provide a device of the character described, designed for the purpose of receiving lint cotton, or other fibrous material from the gin, and separating the dust and other foreign matter 15 therefrom, and forming the lint from a loose and fluffy state into a comparatively compact bat, which is then delivered to the baling press. In the handling of cotton, the lint is first separated from the seed by the 20 gin, and as delivered from the gin, it usually contains considerable dust and other foreign matter. It is desirable that said dust and foreign matter be removed from the lint, and that the lint be converted from a loose and 25 fluffy state into a bat before it is delivered into the baling press. For this purpose, the separator hereinafter described has been designed and embodying a foraminated drum through which an air current is created by 30 suction, carrying with it, the dust and other foreign matter and depositing the lint on the periphery of the drum, and the lint is held on said drum by air pressure and is carried by it between the drum, and bat 35 forming rollers, cooperating with the drum and is thereby formed into a bat before it is delivered into the baling press to be formed into a bale.

Another object of the invention is to provide a separator and condenser of the character described, through which the lint-carrying current is generated by means of a suction fan, or other similar means.

A further feature of the invention resides 45 in the provision of a novel form of flue, through which the lint is conducted from the gin and delivered in a uniform and even mass to the separator and condenser.

A still further feature of the invention resides 50 in the provision of a device of the character described, so constructed that the lint cotton will be carried in and deposited upon the forming drum, by means of suction and formed into a bat, and which is 55 provided with means releasing the bat from

the influence of said air current, to permit the unimpeded discharge of the bat from the condenser.

With the above and other objects in view, the invention has particular relation to certain novel features of construction, operation and arrangement of parts, an example of which is given in this specification and illustrated in the accompanying drawings, 60 wherein:

Figure 1, is a front elevation of the device shown partially in section.

Figure 2, is a rear elevation.

Figure 3, is an end view.

Figure 4, is a fragmentary front elevation. 70

Figure 5, is a fragmentary sectional view, taken on the line 5—5 of Figure 4.

Figure 6, is a fragmentary side elevation of one of the condenser roller bearings. 75

Figure 7, is a sectional view taken on the line 7—7 of Figure 6.

Figure 8, is a transverse sectional view taken on the line 8—8 of Figure 1.

Figure 9, is a longitudinal sectional view, 80 of the condenser roller which is mounted upon and driven by the counter drive shaft, taken on the line 9—9 of Figure 10, and

Figure 10, is a transverse sectional view thereof, taken on the line 10—10 of Figure 85 9.

Referring now more particularly to the drawings, wherein like numerals of reference designate similar parts in each of the figures, the numeral 1, refers to a casing, 90 which is approximately cylindrical in cross sectional contour and the numeral 2, designates an inlet flue, through which the lint is delivered from the cotton gin. The discharge end of this flue is contracted, forming 95 a funnel shaped section 3, from which leads a wide chute 4, which enters the upper part of the casing in the rear. The tapering section 3 is provided so that as the mass of lint cotton enters it from the flue 2, a portion of 100 the lint will be retarded, and the suction through the chute 4 will cause an even distribution of the lint along the tapering section 3, thus causing the cotton to be evenly distributed along the chute and to pass into 105 the casing in an even and uniform mass.

A rotatable drum is mounted within the casing and extends from end to end thereof. This drum is formed of the end castings 5, secured to which are the lengthwise bars 110

6, which are spaced a uniform distance apart, and arranged radially. Around these bars, there is wound spirally, the spring wire 7, around which is wrapped the wire 5 mesh 8, forming the periphery of the drum, thus forming a foraminated drum whose periphery will arrest the cotton but permit the air and the dust and other foreign matter to pass therethrough. Secured to each end 10 of the casing, are the brackets 9, 9, which support the respective bearings 10, 10, through which the sleeves 11, extend. The inner end of each sleeve projects inwardly and beyond the corresponding bearing 10, and 15 each end of the condenser drum, hereinbefore described, has a bearing 12, which is fixed thereto, and which receives the inner ends of and is supported by, the sleeves 11. The outer ends of the sleeves 11 are formed 20 into annular flanges 13, which fit against the outer ends of the bearings 10, and are secured thereto by means of set screws 14, which pass through the oblong slots 15, of said flanges and are tapped into said bearings 10. Adjusting screws 16 are threaded 25 through the projecting fingers 17, formed integral with the bearings 10, and the inner ends of these adjusting screws rest against the rim of the corresponding flange 13. Means is thus provided for adjusting the 30 condenser drum to hold it centered relative to the casing. When it is desired to adjust said drum, the set screws 14, may be loosened and the required adjustment made through 35 the adjusting screws 16, and the set screws 14 then again tightened.

Fastened to each end of the condenser drum, but located outside of the casing are the respective spur gears 18, 18, which are 40 in mesh with the respective spur gears 19, 19, which are fixed upon the drive shaft 20. This shaft is rotatably mounted in suitable bearings carried by the front side of the casing and fixed upon one end thereof, is 45 the pulley 21, through which rotation is imparted to said shaft and thence to the condenser drum. The shaft 20 carries the roller 22, which is in rolling contact with the condenser drum. This roller is fastened to the 50 shaft by means of the spiral springs 23, 23, one arranged at each end within said roller, one end of each spring being attached to the shaft 20, and the other end thereof being secured to the roller 22. The roller 22 is 55 one of a series of bat forming rollers, the other rollers of said series being indicated by the numerals 24. Said rollers 24 are fixed upon the respective shafts 25, whose ends project through the oblong slots 26, in the 60 respective ends of the casing, and are rotatable in the respective sliding bearings 27. These bearings are movable radially with respect to the condenser drum, and move in the tracks 28, 28, secured to the outer side of 65 the end plates of the casing 1. The respec-

tive ends of the shafts 25 carry the spur gears 29, which are in mesh with and rotated by the gear 18. Operating against the bearings 27 are the yieldable seats 30, which normally hold the rollers 24 in rolling 70 contact with the condenser drum, but permit them to move radially relative thereto. Fixed to each end of the casing is a circular band 31, which is arranged concentric with respect to the condenser drum. This band 75 is provided with a plurality of radial arms 32, which are integral therewith, and whose outer ends rest upon the corresponding bosses 33, which project out from the ends of the casing, and said arms are secured to 80 the bosses by means of suitable set bolts, as 34. Fitted within the bands 31, are the inclosing hoods 35, which are secured in position by means of suitable bolts 36, which pass through said hoods and bands. These 85 bolt holes are spaced a uniform distance apart, so that the hoods may be adjusted to any desired position. Leading from the respective hoods 35, are the air tubes 37, 37, which are united in a common suction pipe 90 38. The suction created will operate to carry the lint cotton from the gin through the flue 2, and the chute 4, and the same will be deposited upon the condenser drum, the air current passing through the foraminated 95 periphery of said drum and carrying the dust and other foreign matter with it, and said air will pass out through the ends of the condenser drum into the hoods 35, and thence through the tubes 37 and the pipe 100 38. The condenser drum rotates in the direction indicated by the arrow in Figure 8, and carries the lint cotton deposited thereon around between it and the bat forming 105 rollers 22, and 24, said rollers yielding radially to permit the passage of the bat which is by them compressed and freed from excess air, and is discharged through a discharge opening provided in the bottom of the casing.

In order to release the bat held on the periphery of the condenser drum from the suction of air, so as to permit the discharge thereof, after it is released by the bat forming roller, it is necessary to restrict the air suction to a certain specific sector of the condenser drum. In order to do this, I have fixed within the condenser drum, a cut-off 115 valve, acute in cross section, which extends from end to end of the drum and fits snugly therein. This valve is formed of end plates 39, a plurality of spaced spiders, 40, and a surrounding cover, 41, formed preferably of sheet metal, and supported by said spiders. This cut-off valve is fixed through the medium of the end plates 39, and spiders 40, to the shaft 42. This shaft extends axially, through the condenser drum, and its ends terminate in the sleeves 13, and are supported therein by means of a plurality 120 110 125 130

of adjusting screws 43, which are threaded through the bearing 10, and extend through aligned oblong slots in the corresponding sleeves 13, and whose inner ends support 5 the corresponding ends of said shaft 42. Through the medium of the adjusting screws 43, the shaft 42 and said cut-off valve may be adjusted to the proper position relative to the condenser drum. As illustrated in 10 Figure 8, this valve is provided with a lateral passageway 44, extending from end to end thereof, and said valve limits or restricts the intake of air to a definite area of the condenser drum, and after the bat has passed 15 said area, the suction is cut off and said bat is freed from the influence thereof, and is released from said drum, thus providing for its discharge from the condenser. As illustrated in Figure 8, the top portion only of 20 the condenser drum is exposed to air suction, and as said drum rotates, the lint deposited thereon, is deflected downwardly, by the transverse deflector 45, and passes between 25 said drum and the bat forming rollers as above explained and thence out through the discharge opening 46. In order to prevent the intake of air through said discharge opening 46, and against the bat, which would cause a back pressure and retard the 30 discharge of the bat from the condenser drum, I have provided a plurality of back pressure valves 47, which are anchored to the inside of the casing 1, and extend from end to end thereof. These valves are formed 35 of flexible material, and extend radially with respect to the condenser drum and the inner edges are free, and rest against the front side of the respective bat forming rollers 22 and 24. These valves prevent the 40 passage of any air from the discharge opening 46, up around the condenser drum, thus preventing an air current in opposition to the direction of the movement of the bat.

It is to be observed that the lengthwise 45 bars 6, entirely span the space between the periphery of the condenser drum and the cut-off valve located therein and prevent an air current from entering the discharge opening 46, and passing through the foraminated drum and then up around between it and the said cut-off valve, thus confining the 50 inlet of air to the chute 4.

What I claim is:

1. The combination of a tapering inlet 55 flue, a chute extending along said flue and adapted to receive lint and air therefrom through a suitable opening, a rotary foraminated bat-forming drum, means whereby the lint and air from said chute are conducted to a limited portion of the surface of 60 said drum, air pipes which are connected with the interior of said drum at the ends thereof, means for causing an air current to pass through said inlet flue, chute, drum 65 and pipes, adjustable means within the drum

for preventing the air from passing through the foraminations of the same excepting at a limited area of the surface of the drum, yieldable bat-forming rollers bearing on said drum, means for preventing air from passing 70 between said rollers to the outer surface of the bat which has been formed, and circumferentially yielding means for rotating said bat-forming rollers. 75

2. A device of the character described, including a casing, a tapering inlet flue, a chute leading from the side of the flue and entering the casing through which lint cotton may be discharged into said casing, air tubes leading from the ends of the casing 80 and uniting in a common suction pipe, all forming an air conduit, a foraminated drum rotatably mounted in the casing and an air current generator connected to said pipe, by means of which an air current is created by 85 suction through said conduit, said air current passing through said foraminated drum and causing the deposit of cotton thereon.

3. A device of the character described, including a casing, a flue, a chute leading from the flue and entering the casing through which fibrous material may be discharged into said casing, air tubes leading from the ends of the casing and uniting in a common suction pipe, all forming an air conduit, a 90 foraminated drum rotatably mounted in said casing, an air current generator connected to said pipe and inducing by suction an air current through said conduit, the air passing through the foraminated drum and causing the deposit of said material thereon, and condenser rollers in rolling contact with said drum and operatively geared with and rotated by the drum between which rollers and drum said material is carried by the rotation of the drum and formed into a bat. 95 100

4. A device of the character described, including a casing, a flue, a chute leading from the flue and entering the casing through which fibrous material may be discharged into said casing, air tubes leading from the ends of the casing and uniting in a common suction pipe, all forming an air conduit, a foraminated drum rotatably mounted in said casing, an air current generator connected 110 to said pipe and inducing an air current through said conduit, the air passing through the foraminated drum and causing the deposit of said material thereon, and condenser rollers in rolling contact with said drum and held yieldingly thereagainst and operatively geared with and rotated by the drum between which rollers and drum said material is carried by the rotation of the drum and formed into a bat. 115 120

5. A device of the character described, including a casing, a conducting flue, a chute leading from the flue and entering the casing through which fibrous material may be discharged into said casing, air tubes lead- 125 130

- ing from the ends of the casing and uniting in a common suction pipe, all forming an air conduit, a rotatable foraminated drum mounted in the casing, an air current generator connected to the pipe by means of which an air current is induced by suction through said conduit, and through the foraminated drum, means arranged within the drum limiting the area of the periphery thereof through which said current is permitted to pass, and condenser rollers in rolling contact with, and held yieldingly against said drum, between which rollers and the drum, said material is carried by the rotation of the drum and formed into a bat.
6. The combination of a rotary foraminated bat-forming drum, means whereby lint and air are conducted to a limited portion of the surface of said drum, air pipes which are connected with the interior of said drum at the ends thereof, means for inducing by suction an air current to pass through said drum and pipes, means for preventing the air from passing through the foraminations of the same excepting at a limited area of the surface of the drum, and yieldable bat-forming rollers geared with and bearing on said drum.
7. A device of the character described, including a casing, a flue, a chute leading from the flue and entering the casing through which fibrous material may be discharged into said casing, air tubes leading from the ends of the casing and uniting in a common suction pipe, all forming an air conduit, a foraminated drum rotatably mounted in said casing, a plurality of condenser rollers in successive rolling contact with said drum, between which rollers and drum, said material is carried by the rotation of the drum, and formed into a bat, and back pressure valves fixed to the casing and extending from end to end, thereof, the inner edges of said valves being free and resting against the corresponding condenser rollers.
8. The combination of a rotary foraminated bat-forming drum, means whereby the lint and air are conducted to a limited portion of the surface of said drum, air pipes which are connected with the interior of said drum at the ends thereof, means for causing an air current to pass through said drum and pipes, means for preventing the air from passing through the foraminations of the same excepting at a limited area of the surface of the drum, bat-forming rollers bearing on said drum, and means for preventing air from passing between said rollers to the outer surface of the bat which has been formed.
9. The combination of a rotary foraminated bat-forming drum, means whereby the lint and air are conducted to a limited portion of the surface of said drum, air pipes

which are connected with the interior of 65 said drum at the ends thereof, means for causing an air current to pass through said drum and pipes, means for preventing the air from passing through the foraminations of the same excepting at a limited area of 70 the surface of the drum, bat-forming rollers bearing on said drum, and circumferentially yielding means for rotating said bat-forming rollers.

10. The combination of a rotary foraminated bat-forming drum, means whereby the lint and air are conducted to a limited portion of the surface of said drum, air pipes which are connected with the interior of 75 said drum at the ends thereof, means for causing an air current to pass through said drum and pipes, means for preventing the air from passing through the foraminations of the same excepting at a limited area of 80 the surface of the drum, a series of bat-forming rollers bearing on said drum, and back pressure valves bearing on said rollers for preventing air from passing between said rollers to the outer surface of the bat which has been formed.

11. The combination of a rotary foraminated bat-forming drum having radial bars 6, means whereby the lint and air are conducted to a limited portion of the surface of said drum, air pipes which are connected 95 with the interior of said drum at the ends thereof, means for causing an air current to pass through said drum and pipes, means within the drum contacting with said bars for preventing the air from passing through the foraminations of the drum excepting at a limited area of its surface, bat-forming rollers bearing on said drum, and means for preventing air from passing between said rollers to the outer surface of the bat which 100 has been formed.

12. The combination of a rotary foraminated bat-forming drum, means whereby the lint and air are conducted to a limited portion of the surface of said drum, air pipes 110 which are connected with the interior of said drum at the ends thereof, means for causing an air current to pass through said drum and pipes, means for preventing the air from passing through the foraminations 115 of the same excepting at a limited area of the surface of the drum, means at successive points around the drum for pressing the lint against the same to form a bat, and means for preventing air pressure on the outer surface of the bat which has been formed.

In testimony whereof, he has signed his name to this specification in the presence of two subscribing witnesses.

JAMES C. GARNER.
